UNITED STATES PATENT OFFICE.

HIRAM A. HATFIELD, OF NOGALES, ARIZONA, ASSIGNOR, BY MESNE ASSIGNMENTS, TO INTERNATIONAL AIR-BRAKE COMPANY, OF WILMINGTON, DELAWARE, A CORPORATION OF DELAWARE.

VALVE MECHANISM.

1,149,259.

Specification of Letters Patent Patented Aug. 10, 1915.

Application filed November 2, 1914. Serial No. 869,795.

To all whom it may concern:

Be it known that I, HIRAM A. HATFIELD, a citizen of the United States, and a resident of Nogales, in the county of Santa Cruz and State of Arizona, have made certain new and useful Improvements in Valve Mechanisms, of which the following is a specification.

My invention relates in general to improvements in valve mechanisms for fluid pressure brakes such as are usually operated by compressed air, and it consists in the combinations, constructions, and arrangements herein described and claimed.

An object of my invention is to provide a device which can be used in connection with an automatic triple valve for setting the brakes with straight air by applying over-charge air pressure from the main reservoir on the engine to the train line air pressure connection through the engineer's brake valve.

Another object of my invention is to provide an improved apparatus of the type described which will act perfectly, regardless of the weight or tonnage of a car or the different train line pressures.

Other objects and advantages will appear in the following specification and the novel features of the device will be particularly pointed out in the appended claims.

In my prior application filed July 27, 1914, Serial #853,501 I have shown the cylindrical piston valve which admits the air to the brake cylinder in a horizontal position directly below the main valve chamber. The present invention is an improvement on this valve in that the cylindrical piston valve is placed in a vertical position at the side of the main valve, which gives a more graduated control, and the port through the piston valve permits it to return to its normal position by gravity.

My invention is illustrated in the accompanying drawing forming part of this application in which—

Figure 1 is a diagrammatic plan view showing the central vertical section through the device, Fig. 2 is a cross section view 50 along the line 2—2 of Fig. 1.

In the following specification I will describe completely the novel valve mechanism and the operation thereof, and only so much of the ordinary mechanism which 55 coöperates therewith as will be sufficient

for a clear understanding of the use and operation of my invention.

In carrying out my invention I provide a valve casing 1 of suitable shape. In the present instance I have shown this as a cylinder having a top 2 which may be secured to the body portion in any suitable manner. Within the interior of the valve casing is a valve member 4. This consists of a weight which is provided at its upper end with a closure 4^y arranged to cover a port 5 which is connected with the auxiliary reservoir. Packing rings 6 are provided for the weighted valve. A lower closure member 4^x is designed to control a port 7 and a passage 18. A by-pass 8 is arranged in the wall of the casing 1 for a purpose herein-after explained. A seepage groove 22 connects with the top portion of by-pass 8 to allow a gradual equalization on opposite sides of the valve of the excess air contained in the auxiliary reservoir when the train line is reduced to normal pressure. In the body portion 1 at the side of chamber in which the valve 4 operates is a cylindrical bore 9 in which is disposed a cylindrical valve piston 10. A passage 18 communicates with the lower portion of the valve chamber in which valve 4 operates and the cylindrical bore 9. A screw plug 11 is provided for closing the end of the bore. The valve 10 has a projecting portion 10^x for limiting the movement of the valve toward the plug. At 12 is shown an exhaust port. A passage 13 communicates with the interior portion 9 of the bore at both ends of cylindrical valve piston 10 and with passage 14. The passage 14 in turn communicates with the brake cylinder either through the exhaust port of the triple valve or can be connected direct by the use of a double check valve to control both exhaust ports.

From the foregoing description of the various parts of the device the operation thereof may be readily understood.

When an overcharge of air pressure is supplied to the train line through the engineer's valve to set the brake, passage 17 being connected directly to the drain plug of the automatic triple valve, air passes 105 from the train line through the passage 17 and port 7 where it unseats the weighted valve 4. This allows the air to pass lower valve member 4^x thence by means of the passage 18 into the bore 9, thus forcing the 110

piston valve 10 to the projecting portion 20 at the top of bore 9. This uncovers the passage 13 and covers the exhaust port 12. The air now flows through the passage 13 and is delivered through passage 14 to the exhaust port of the triple valve and on to the brake cylinder, thereby setting or applying the brakes. It will be understood that one of these improved straight air valve mechanisms will be used in connection with the automatic triple valve on each individual car.

When the train line air pressure is again reduced to normal pressure through the engineer's valve, the weighted valve 4 seats on port 7 and passage 18, the vent 19 through cylindrical valve piston 10 permits it to fall to its normal position which then opens the exhaust port 12 releasing air from brake cylinder to the atmosphere, thus releasing the brake.

It will thus be seen that it depends entirely on the amount of overcharge air pressure which the engineer adds to the train line air pressure how hard the brakes are set, as he has complete control over this by the use of the engineer's brake valve on the engine.

As before mentioned, by the use of my straight air valve mechanism the brakes can be applied by both the use of straight air and automatic air. Straight air can be applied to the brakes and automatic air applied on top, or automatic air can be applied to the brakes and straight air can be applied on top, but with my valve it is better to use straight air in all cases, thereby having the automatic air in reserve in case of accident, such as the parting of a hose connection or the breaking of a train pipe. As is clearly seen, the auxiliary reservoir is kept charged by the use of my valve.

With the present system of automatic air brakes it often happens on long grades that the automatic air pressure contained in the auxiliary reservoir is not sufficient to hold heavy trains when making continuous applications and having to bring the brakes to full release before being able to recharge the auxiliary reservoir, whereas by the use of my valve the engineer can apply the brakes by the use of the overcharge air pressure sufficient to hold the train, and at the same time have the automatic air in reserve to set the brakes in case of accident as mentioned above.

By the use of my valve it is impossible to lose the braking power since any position other than running and lap positions of the engineer's brake valve will set the brakes. Also by the use of my valve using the straight air, the pressure in each brake cylinder will be the same, whether the brake cylinder piston is set to travel five inches or ten inches, for the reason that the overcharge

air pressure applied at the engine is distributed equally through my valve to the brake cylinders. This prevents to a large extent, the parting or breaking in two of the train, as is now very often the case with the present system of automatic air.

As has been explained above in order to set the brakes with my attachment, the engineer applies an overcharge of air pressure to the train line pressure. In order to set the brakes with automatic air as now used he reduces the train line pressure. It will be seen that he can set the brakes either with straight or automatic air by the use of the same handle of the brake valve now used on the engine as he may see fit.

The by-pass 8 is arranged in the wall of casing 1 for the purpose of allowing the auxiliary reservoir air pressure coming through port 5 to be equalized on both sides of the weighted piston valve 4 when it is seated on port 7 and passage 18. This reduces the weight of the valve so that it will act perfectly, regardless of the weight or tonnage of a car or the different train line pressures, and permits of a gradual control by the overcharge of air pressure in the train line for a straight air application of the brakes.

Having now described my invention, what I claim as new and desire to secure by Letters Patent is:—

1. In an air brake system, a fluid pressure valve mechanism for air brakes comprising a casing provided with a valve chamber, a weighted valve subject to train pipe and auxiliary reservoir air pressure in said chamber for controlling the flow of train pipe air pressure to the brake cylinder, a passage from said valve chamber to the brake cylinder provided with an exhaust port, a piston valve in said passage provided with a through port operated by the flow of air pressure to the brake cylinder to close said exhaust port and by gravity to open said exhaust port as the air pressure equalizes through said through port.

2. In an air brake system, a fluid pressure valve mechanism for air brakes comprising a casing provided with a main valve chamber, a weighted valve disposed in said chamber, packing rings for said valve, a pipe for establishing communication between said main valve chamber and the auxiliary reservoir, a by-pass in the wall of the casing around said valve when the latter is in its lower position, a seepage groove in the wall of said casing and connecting with the upper end of the said by-pass, a pipe for connecting one end of said valve casing with a supply of compressed air, a passage leading from said pipe normally closed by said weighted valve and adapted to be uncovered by an overcharge of air pressure in the passage, an outlet pipe establishing com-

munication with the brake cylinder, means for establishing communication between said main valve chamber and said outlet pipe, said means comprising a piston disposed within a bore in said valve casing, a passage connecting said main valve casing with said bore, a passage arranged to be uncovered by the movement of said piston valve for connecting said bore with said outlet pipe, an exhaust port normally uncovered and adapted to be covered when the piston valve uncovers the passage between the interior of the bore and the outlet pipe,

said exhaust passage being uncovered by the movement of said piston valve to normal position, a screw plug at the lower end and a projection in the casing at the upper end of said bore for limiting the movement of said piston valve and a port through the center of said piston valve for permitting its return to normal position.
